UNITED STATES PATENT OFFICE

133,656

DESIGN FOR AN EMBROIDERED TRIMMING

Herman Krieger, Brooklyn, N. Y.

Application August 1, 1942, Serial No. 107,785

Term of patent 3½ years

To all whom it may concern:

Be it known that I, Herman Krieger, a citizen of the United States, residing at Brooklyn, county of Kings, city and State of New York, have invented a new, original, and ornamental Design for an Embroidered Trimming, of which the following is a specification, reference being had to the accompanying drawing, forming part thereof, wherein the figure is a plan view of an embroidered trimming, showing my new design, with a unit of design outlined in dot and dash lines.

I claim:

The ornamental design for an embroidered trimming, substantially as shown and described.

HERMAN KRIEGER.
